UNITED STATES PATENT OFFICE.

RUSSELL HUFF, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN.

HYDROCARBON-MOTOR.

1,082,527.

Specification of Letters Patent.

Patented Dec. 30, 1913.

Original application filed July 2, 1909, Serial No. 505,735. Divided and this application filed March 30, 1912. Serial No. 687,375.

To all whom it may concern:

Be it known that I, RUSSELL HUFF, a citizen of the United States, and resident of Detroit, Wayne county, State of Michigan, have invented certain new and useful Improvements in Hydrocarbon - Motors, of which the following is a specification.

This application is a division of my application, Serial No. 505,735, filed July 2, 1909. 10. This invention relates to the manner of cooling the cylinders of internal combustion engines and particularly to cooling engines of the sliding sleeve valve type.

A feature of this invention consists in the construction of the cylinder head, which is cored so as to provide a water space and is provided with raised portions forming inlet and discharge passages connecting with the water space in the head. The head is of 15 dished formation and by providing these raised portions the total depth of this dished portion which receives the spark plug is reduced thereby rendering the plug more accessible.

25. In the drawings: Figure 1 is a vertical transverse section of a sleeve valve motor; Fig. 2 is a top plan view of one of the cylinders of such a motor, and Fig. 3 is a section on the line 3 of Fig. 2; Fig. 4 is a longitudinal transverse section through part of a cylinder taken on the line 4—4 of Fig. 3, and Fig. 5 is a side elevation of the cylinder head removed from the cylinder.

Referring to the drawings, 11 designates 35 the upper section of the crank case provided with integral side arms 12 for supporting the engine structure from the side bars of a motor vehicle, 13 the intermediate section, and 14 the lower section of the crank case. 40 The crank shaft 15 is journaled in bearings between the sections 13 and 11. All of the sections are bolted together in a manner well understood by those skilled in the art.

The cylinders 16 are bolted to the crank 45 case. These cylinders in the construction shown are cast in pairs. Each cylinder is provided with a cylinder head 17, provided with a downwardly extended portion 18 of smaller diameter than the internal diameter 50 of the cylinder, thereby forming an annular space or chamber 19. The downwardly projecting portion 18 is provided with the usual packing rings. Each cylinder head is pro-

vided with two concentric annular water spaces 35 and 35', the space 35 being within 55 the bore of the cylinder and the space 35' being in axial alinement with the cylinder wall. These water spaces are connected by the passages 34 and 36 and are so spaced as to provide an extension of the annular space 60 in which the sleeve valves are located. An inner valve sleeve 20 and an outer valve sleeve 21 are mounted to slide on each other in the cylinder. These valve sleeves are provided with ears 22, and connecting rods 23 65 connect these ears with the eccentrics 25 mounted upon the valve shaft 24. These eccentrics are shown diagrammatically in Fig. 1 and are placed about eighty degrees apart. The sleeves are provided with inlet 70 ports 28 and exhaust ports 29, communicating with the inlet 30 and exhaust 31 respectively. The operation of the valves thus described will be obvious from the arrangement shown in Fig. 1. The cylinders are 75 provided with water jacket spaces 32. Each one of the cylinders is provided with a shallow elbow 33, communicating with the passage 34 and with the cavity 35 in the head. A discharge duct 36 upon the opposite side 80 of the cylinder communicates with the pipe 37 leading to the radiator. The inlet duct or channel 34 and the outlet duct or channel 36 are formed by raised portions on the cylinder head, this construction being clearly 85 shown. By means of this construction the depth of the recessed portion 38 is decreased, and the spark plug 39 is rendered accessible so that it may be engaged by the ordinary wrench. This construction has a decided 90 advantage over those constructions in which the cylinder head is provided with an annular space communicating with the cavity 35.

What I claim is:

1. In a hydrocarbon engine, a one-piece cylinder head cored to provide a water jacket, and provided with narrow raised portions forming oppositely arranged inlet and discharge ducts communicating with the cavity. 95
2. In a hydrocarbon engine, in combination, a cylinder head cored and dished to provide an annular water jacket cavity, a spark plug secured into the center of the head, said head being provided with nar-

row raised portions forming oppositely arranged inlet and discharge ducts communicating with the cavity.

3. In a hydrocarbon engine, a cylinder, a head secured to the cylinder and having communicating concentric water chambers, and an annular space between said water chambers adapted to receive a sleeve valve, the outer of said chambers being in axial

alignment with the cylinder wall and the inner chamber being extended axially within the bore of the cylinder.

In testimony whereof I affix my signature in presence of two witnesses.

RUSSELL HUFF.
